[57] CLAIM

The ornamental design for a container, as shown and described.

DESCRIPTION

FIG. 1 is a side elevational view of a container showing our new design;

FIG. 2 is a sectional elevational view thereof taken along line 2—2 of FIG. 1;

FIG. 3 is a side elevational view of a second embodiment of FIG. 1;

FIG. 4 is a sectional elevational view of FIG. 3 taken along line 4—4;

FIG. 5 is a side elevational view of FIG. 1 except with both the nozzle and the bottom cap removed for clarity of illustration;

FIG. 6 is a sectional elevational view of FIG. 5 taken along line 6—6;

FIG. 7 is a side elevational view of a third embodiment of FIG. 1;

FIG. 8 is a sectional elevational view of FIG. 7 taken along line 8—8;

FIG. 9 is a bottom plan view of FIGS. 1, 3 and 7;

FIG. 10 is a top plan view of FIG. 1;

FIG. 11 is an enlarged scale fragmentary sectional elevational view of FIG. 6 taken along line 11—11;

FIG. 12 is a bottom plan view of the nozzle cap in FIG. 1, shown separately for clarity of illustration;

FIG. 13 is a side elevational view of FIG. 12;

FIG. 14 is a top plan view of FIG. 12;

FIG. 15 is a perspective view of FIG. 12;

FIG. 16 is a bottom plan view of the cap in FIG. 3, without the nozzle, shown for clarity of illustration;

FIG. 17 is a side elevational view of FIG. 16; and,

FIG. 18 is a perspective view of FIG. 16.
